UNITED STATES PATENT OFFICE.

ERNEST M. WHITE, OF GLOBE, ARIZONA.

SPLASH-TROUGH FOR OILING SYSTEMS.

1,109,724.

Specification of Letters Patent.

Patented Sept. 8, 1914.

Application filed September 9, 1913. Serial No. 788,832.

To all whom it may concern:

Be it known that I, ERNEST M. WHITE, a citizen of the United States, and a resident of Globe, Gila county, Arizona, have invented certain Improvements in Splash-Troughs for Oiling Systems, of which the following is a specification.

One object of my invention is to provide a novel form of auxiliary container or reservoir designed to be attached to or form part of a crank case such as is commonly employed on automobile or marine engines or motors, the construction being such as to provide an increased depth of oil at those parts thereof from which oil is dipped or splashed up by a connecting rod of the motor, when the latter is inclined in any direction.

It is further desired to provide a splash trough or auxiliary reservoir having the above noted characteristics, which shall be relatively simple and inexpensive in construction and which may be conveniently applied to the crank case of the motor in any desired number depending upon the number of cranks, etc., which it is required to lubricate.

These objects and other advantageous ends I secure as hereinafter set forth, reference being had to the accompanying drawings, in which:

Figure 1, is a transverse vertical section of an engine crank case showing my invention as applied thereto; Fig. 2, is a plan of the various parts shown in Fig. 1; and Figs. 3 and 4, are vertical sections taken respectively on the lines *a—a* and *b—b*, Fig. 2, further illustrating the construction of my invention.

In the above drawings, 1 represents the lower part of the crank case of an engine or motor such for example as is commonly used for the propulsion of motor vehicles or boats, and while such an engine may have any number of connecting rods 2 I have illustrated but two of these in the present instance. These rods are operatively connected to the cranks on the main shaft 3 of the motor or engine, and each of them has at its lower end a downwardly projecting piece 4 constituting a finger or dipper for collecting and splashing up oil from an auxiliary reservoir 5 mounted in or forming an integral part of the crank case structure 1. In the case illustrated there is one of

these auxiliary reservoirs 5 for each of the connecting rods 2, and as shown, each reservoir is removably held to columns or brackets 6 projecting upwardly from the bottom of the crank case 1, by means of bolts 7. 60 Each of the auxiliary reservoirs 5 is formed in the shape of a relatively shallow, substantially rectangular box or container elongated transversely of the crank case 1 and supported in such a position that when its co-acting connecting rod 2 is at the lowest portion of its stroke; its dipper 4 will extend below the surface of the oil contained in the said reservoir.

At the ends 8 of the auxiliary reservoir 70 I provide level determining overflow openings 9 and 9^a whose bottom edges are at the height at which it is desired to normally maintain the oil level and it is noted that said openings are formed in diametrically 75 said openings are formed in diametrically opposite parts to the two ends 8, preferably in reservoir. Adjacent the ends and along opposite sides of the auxiliary reservoir 5, I provide two L-shaped troughs 10 and 10^a, 80 so designed that each of them receives the oil flowing out of one of the overflow openings 9 or 9^a. The extremity of each trough 10 or 10^a most distant from its opening 9 or 9^a is in turn provided with a level determining overflow opening 11 or 11^a, as the case may be, whose bottom edge is at substantially the same level as the bottom edges of said overflow openings 9 and 9^a. With such an arrangement of parts, the oil entering 90 one of the troughs at a point adjacent one side of the auxiliary reservoir 5, is conducted along the opposite side thereof so as to be ultimately discharged at some point adjacent said side, it being noted that each of the troughs holds a small quantity of oil. The length of the side portion of each trough is immaterial so that it extends beyond the center of said auxiliary reservoir 5. 95

A pump driven from any suitable part of the engine or motor through a rod 13, has its intake connected through a screened inlet pipe 14 to the lower portion of the crank case 1 which forms a main reservoir receiving the overflow from the openings 11 and 11^a of the auxiliary reservoirs; the discharge pipe 15 of the pump being connected to a distributing pipe 16 to which are connected delivery pipes 17 discharging 100 into the various auxiliary reservoirs. 110

Under operating conditions, each of the connecting rods 2 operates in a plane passing through the longitudinal axis of its auxiliary reservoir 5, and since the pump 5 continuously delivers oil to all of the auxiliary reservoirs, the latter are normally filled with oil to a constant level determined by the height of the bottom edges of the overflow openings 9 and 9^a. The dipper 4 on each rod therefore enters the oil in its reservoir at each revolution, and collects and splashes up a certain quantity thereof so as to lubricate the parts of the engine or motor in a well known manner. The surface 10 plus oil not splashed up passes through the overflow openings 9 and 9^a into the troughs 10 and 10^a, from whence it flows through the overflow openings 11 and 11^a back to the main reservoir formed by the crank case 1. If under conditions of operation the crank case should be laterally inclined, as for example, when the motor vehicle on which it is mounted has its wheels on one side in a rut, the oil in each of the auxiliary reservoirs runs toward one end of the same, and while a portion of the oil in one of the troughs, 10 for example, is at once discharged into the main reservoir through its overflow opening 11, the oil in the other trough 10^a flows to the end portion of the same and through the overflow opening 9^a thereof is added to the oil body in the auxiliary reservoir thus raising its level. The overflow 11^a now being higher than the level 35 of oil in reservoir 5, no oil will flow through the troughs 10^a or 10 until the pump has raised the oil level in said reservoir to a point from which it may overflow as above described. As a result the dipper 40 4 of the connecting rod at each revolution extends deeper into the oil and consequently splashes up a greater amount of the same, as is desirable under the conditions noted. Obviously, if the motor is transversely inclined in an opposite direction, the second trough 10 serves to cause an increased depth of oil as just explained. Again if the motor vehicle or boat on which the motor is mounted should be longitudinally inclined, 45 there would result a transverse inclination of all of the auxiliary reservoirs, and while as before the oil in one of the troughs as 10, for example, would shortly be discharged through its overflow opening 11, the greater part of the oil in the other trough 10^a would collect in the end portion thereof and flow through its overflow opening 9^a into the body of the reservoir. The overflow 9 now being higher than the level of oil in the 50 reservoir 5 there is no flow of oil through overflow 11^a until the pump has raised the level of oil in said reservoir 5 to the level of said overflow 11^a. As before, the dipper on the connecting rod would extend more deeply into the oil than under normal con-

ditions so that large quantities would be splashed up to provide the additional lubrication required, when, for example, the vehicle was ascending a grade.

In any of the cases above noted the return of the motor to its normal level position is at once followed by the discharge of the surplus oil in the auxiliary reservoir into the two troughs 10 and 10^a so that the connecting rod merely splashes up the predetermined quantity of oil from the body thereof in the reservoir wherein it is maintained at the desired depth as above indicated.

I claim:

1. The combination of a splash trough for an oiling system; and means for causing a body of oil to have a predetermined depth in said splash trough regardless of its inclination within operating limits, from a normal position, the same consisting of a duct communicating with the splash trough at one end thereof and discharging adjacent one side of said splash trough.

2. The combination of an auxiliary container for a splash oiling system, and means for causing a body of oil to have a predetermined depth therein regardless of its inclination from a normal position within predetermined limits, the same consisting of a trough communicating with the container at one end thereof and discharging adjacent the side of said container; a main container for collecting the oil discharged from the auxiliary container; and means for supplying oil from the main container to said auxiliary container.

3. The combination of a container for a splash oiling system, and means for causing a body of oil to have a predetermined depth therein regardless of its inclination from a normal position within operating limits, the same consisting of a trough communicating with the container at one end thereof through a level maintaining overflow opening and discharging adjacent the side of said container through a second level maintaining overflow opening.

4. The combination of a container for a splash oiling system, and means for causing a body of oil to have a predetermined depth therein regardless of its inclination within operating limits from a normal position, the same consisting of a trough communicating with the container at one end thereof and discharging adjacent the side of said container through a level determining overflow opening.

5. The combination of an auxiliary reservoir for an oiling system; with an L-shaped trough having an overflow opening at one side of said reservoir and connected to receive oil from or deliver it to the reservoir at one end thereof.

6. The combination of an auxiliary reser-

voir for an oiling system, with two troughs each extending along one end and a side of said reservoir, said troughs having overflow openings at opposite sides of the reservoir and being respectively connected to said reservoir at the opposite ends thereof.

7. The combination of an auxiliary reservoir for a splash oiling system with two ducts each extending along one end and a side of said reservoir, said ducts having overflow openings at opposite sides of the reservoir and being respectively connected to said reservoir at diametrically opposite portions of the ends thereof.

15 8. The combination of an auxiliary reservoir for an oiling system having openings at its opposite ends; troughs respectively connected to receive oil from or deliver it to said openings and having discharge openings respectively on the opposite sides of the reservoir; a main reservoir under said auxiliary reservoir; and means for delivering oil from the main reservoir to the auxiliary reservoir.

25 9. The combination of a crank case; a plurality of auxiliary reservoirs mounted therein in positions to respectively receive moving parts of an engine; and means for causing bodies of oil in said auxiliary reservoirs 30 to have predetermined depths when the crank case is inclined in any direction, the same consisting of two troughs for each auxiliary container, each extending adjacent one end and one side thereof, each trough 35 communicating with its auxiliary container at one end thereof and having a level determining overflow opening on one side of said container; with a pump connected to deliver oil from the crank case to the several 40 auxiliary containers.

10. The combination of a moving member of an engine; an oil containing reservoir mounted to be periodically entered by said member; and means for automatically supplying an additional quantity of oil to the

reservoir both when it is inclined longitudinally and when it is inclined transversely.

11. The combination of a moving member of an engine; an oil containing reservoir mounted to be periodically entered by said member; a main reservoir; with oil holding conduits interposed between said two reservoirs in position to automatically supply an additional quantity of oil to the first reservoir both when it is inclined longitudinally and when it is inclined transversely.

12. The combination of a main reservoir for a splash oiling system; an auxiliary reservoir having an opening at one end; a duct communicating with said opening and extending along one side of the reservoir to an outlet beyond the middle thereof; and means for transferring oil from the main reservoir to the auxiliary reservoir.

13. The combination of an auxiliary reservoir for a splash oiling system; with ducts each extending along one end and a side thereof and each connected to receive oil from said reservoir, the inlet and outlet of each of said ducts being adjacent diametrically opposite portions of said auxiliary reservoir.

14. The combination of a main reservoir for an engine oiling system; an auxiliary reservoir; with ducts each extending along one end and one side of the auxiliary reservoir, the inlet and outlet ends of each of said ducts being adjacent diametrically opposite portions of said auxiliary reservoir, said ducts being placed to receive oil from the auxiliary reservoir and discharge it into the main reservoir and means for splashing oil out of said auxiliary reservoir.

In testimony whereof, I have signed my name to this specification, in the presence of two subscribing witnesses.
